UNITED STATES PATENT OFFICE.

ARTHUR LE BLANC, OF WORCESTER, MASSACHUSETTS, ASSIGNOR OF ONE-HALF TO JOSEPH LABINE, OF NASHUA, NEW HAMPSHIRE.

ANTIFROSTING ATTACHMENT FOR CAR-WINDOWS.

SPECIFICATION forming part of Letters Patent No. 732,087, dated June 30, 1903.

Application filed February 12, 1903. Serial No. 143,002. (No model.)

To all whom it may concern:

Be it known that I, ARTHUR LE BLANC, a citizen of the United States, residing at Worcester, in the county of Worcester and State of Massachusetts, have invented a new and useful Antifrosting Attachment for Car-Windows, of which the following is a specification.

This invention relates to a construction which has been designed with a view of facilitating the running of electric cars or for other purposes by preventing windows from frosting or moisture from collecting thereon in such a manner as to obstruct the view of the motorman.

15 To these ends this invention consists of the antifrosting attachment which has been especially devised for application to electric-car windows or which may be used in other locations.

20 In the accompanying drawings, Figure 1 is a perspective view of sufficient parts of a car to illustrate the application of my invention thereto. Fig. 2 is an enlarged perspective view of my antifrosting attachment, and Fig. 25 3 is an enlarged fragmentary view thereof.

In the operation of electric cars or in other situations where it is necessary to maintain an outlook through exposed windows or panes of glass a source of considerable difficulty 30 and in some cases even danger is due to the frosting of the window-panes or the collection of moisture thereon in such a manner as to obscure the vision and interfere with the safety of the car and its passengers.

35 The especial object of my present invention is to provide an antifrosting attachment for car-windows which is designed to secure a circulation of heated air in such a manner that the windows may be kept absolutely free from 40 moisture or may be dried off as frequently as required.

To these ends an attachment constructed according to my invention consists, essentially, of a heating-coil which is inclosed in 45 the space between the inside and outside window-frames. This heating-coil is preferably supplied with current from the trolley-circuit, and coöperating with the heating-coil I 50 preferably provide draft-inlets controlling the circulation of air through the air-space be-

tween the window-panes. A cut-out device is also preferably provided, so that the heating-coil need not be operated except when it is desired to dry or warm the air-space between the window-panes.

55 Referring to the accompanying drawings for a detail description of an antifrosting attachment constructed according to my invention, A designates an ordinary electric car. In the present instance the car A has a vestibule or closed forward end.

Secured on the front of the car, so as to overlap and form a protecting double window for the front pane of the car-vestibule, is an attachment constructed according to my in- 60 vention.

65 As herein illustrated, my antifrosting attachment comprises an outside sash or frame 10, which may be applied to the front of the car by means of clips or small angle-irons 11. 70 Opening through the front of the lower bar of the sash 10 are a number of inlets 12, and opening through the top bar of the sash 10 are outlets 13. As shown most clearly in Fig. 3, the lower bar of the sash is provided 75 with an overhanging bead 14, and secured in place by the bead 14 is a perforated slide or damper 15, the holes through which coöperate with the air-inlets 12. The slide 15 is held in place by a retaining-strip 16. 80

Mounted in the frame 10 and extending across the air-inlets 12 is a heating-coil 17. The heating-coil 17 is preferably supplied by a shunt from the trolley-circuit, and the current for the heating-coil may be turned on or 85 off by the switch 18.

90 By means of this construction the space between the panes of glass at the front of an electric car may be heated or dried as frequently as required, or a sufficient circulation of heated air may be maintained there-through to efficiently prevent the frosting or collection of moisture on the window-panes, and by means of this construction a motorman may retain an unobstructed view of the 95 track, even in severest weather.

I am aware that changes may be made in practicing my invention and that my attachment may be used for other purposes besides that of application to electric cars. I do not 100

desire, therefore, to be limited to the construction I have herein shown and described; but

What I do claim, and desire to secure by 5 Letters Patent of the United States, is—

An antifrosting attachment for car-windows, comprising a casing adapted to be secured to the front of a car to protect a front window thereof, inlet-holes opening through 10 the lower bar thereof, a perforated slide controlling the inlet-holes, outlet-holes through

the top bar of the casing, an electric heating coil mounted in the lower part of the casing over the air-inlet holes, and a switch for controlling the operation of the heating-coil.

15

In testimony whereof I have hereunto set my hand in the presence of two subscribing witnesses.

ARTHUR LE BLANC.
